US00D993182S

(12) **United States Design Patent** (10) **Patent No.:** **US D993,182 S**
(45) **Date of Patent:** **** Jul. 25, 2023**

(54) **ELECTRICAL CONNECTOR**

(71) Applicant: **Amphenol Corporation**, Wallingford, CT (US)

(72) Inventors: **Rakesh Thakare**, Cary, NC (US); **Caichun Song**, Changzhou (CN)

(73) Assignee: **AMPHENOL CORPORATION**, Wallingford, CT (US)

(**) Term: **15 Years**

(21) Appl. No.: **29/724,964**

(22) Filed: **Feb. 20, 2020**

(57) **CLAIM**

The ornamental design for the electrical connector, as shown and described.

DESCRIPTION

FIG. 1 is a perspective view of an electrical connector in accordance with the present design;

FIG. 2 is a front elevational view of the electrical connector illustrated in FIG. 1;

FIG. 3 is a rear elevational view of the electrical connector illustrated in FIG. 1;

FIG. 4 is a right side elevational view of the electrical connector illustrated in FIG. 1;

FIG. 5 is a left side elevational view of the electrical connector illustrated in FIG. 1;

FIG. 6 is a top plan view of the electrical connector illustrated in FIG. 1; and,

FIG. 7 is a bottom plan view of the electrical connector illustrated in FIG. 1.

The broken lines in the drawings illustrate portions of the electrical connector that form no part of the claimed design.
